3 Claims. (Cl. 250—27)

This invention relates to a new and novel safety device for electron tubes cooled by water circulation, and is concerned with a safety device designed to protect electron tubes of large power which are normally cooled by a current of water, from overheating.

A water-cooled power-tube consists generally of a glass bulb or tube welded onto a metal cylinder which constitutes the anode or plate. The latter is immersed in a metallic vat in which cooling water is circulated. The plate and the vat being operated at a high potential (say, 10,000 volts above ground), coils consisting of insulation material are placed between the said vat and the water conduit which feeds the same, the insulation consisting of caoutchouc, steatite, and the like.

To check up on the rise of the temperature of the plate, and in order to act upon the safety devices such as electric bells, circuit breakers, etc., there is usually connected in the water-circulation pipe or conduit a means responsive to variations in temperature, such as a contact-type thermometer, a bimetal leaf or spring, or the like. However, in order to avoid the said safety circuits and means being subjected to the action of the high voltage of the plate or to avoid the necessity of the same being insulated against such a high potential, general practice of the past has been to mount the means sensitive to temperature fluctuations beyond the insulating coils, that is to say, sensibly at ground potential.

This arrangement, however, involves the inconvenience that, as a result of thermal radiations which take place along the coil (and this radiation is not negligible and is a function of the ambient temperature) the indications available at the end of the coil do not give a direct or true picture of the state of heating of the anode. In other words, the operation of the safety devices will or may be vitiated.

In order to obviate the said difficulty, according to the present invention, the control or check-up device (consisting in practice, e. g. of a contact actuated by a bimetallic strip or spring) is disposed in the water current conduit at the very outlet in the anode vat; however, at the same time all direct electric connection between the said means and the apparatus controlled thereby (alarm bell and supply source therefor, coil of circuit-breaker, etc.) is avoided.

An assembly of the said kind may be carried into practice by the aid of a photoelectric cell and an ordinary glow-lamp fed by virtue of radio-frequency induction. The attached figure, by

way of example, shows a preferred embodiment of the basic idea of the invention and is intended to give a clearer understanding of the invention.

Referring to the drawing, A denotes the water-cooling vat of the anode or plate. This vat is traversed by a water current indicated by the arrows. The water supplied from general water mains or from a special pump flows first through the insulation coil E, then across the said vat A, flows in contact with the elements responsive to temperature variations, such as a bimetallic strip T, for instance, controlling an electric contact D, and leaves through the second insulation coil F.

In order to preclude all chances of direct electric connection between the contact D and the safety or check-up means to be actuated thereby, according to the embodiment here illustrated, the scheme includes an ordinary illuminating or glow-lamp B fed on radio-frequency energy and a photoelectric cell C. The very proximity of the contact D and the insulating circuits makes it very easy to collect by virtue of induction in an inductance S disposed in the neighborhood of the contact D a sufficient volume of radio-frequency energy to cause lighting of the bulb or lamp B. The circuit of this lamp includes, therefore, only the inductance S and the contact D, and this circuit may be easily insulated from ground. Its electrostatic potential moreover depends upon the connection I which unites a point of the inductance S with the vat A, the two terminals of the contact D being, themselves, insulated from the vat.

The operation of the arrangement here disclosed is then as follows: with the coil S being placed inside a radio-frequency field, it becomes the seat of an induced electromotive force sufficiently great to raise the lamp B to a state of incandescence. Hence, the latter will be lit when the contact D is closed as a result of an undue rise of temperature. The light flux of the lamp B coming to strike the photoelectric cell C sets up across the terminals of the same a certain potential which, in turn, causes the arising of a current in the winding of a first, fairly sensitive, relay R1. The latter will occasion closure of the contact a which energizes the coil of another relay R2 fed from the line Z. The relay R2 becomes closed in turn and acts upon the contacts b, c, d. The contact b upon opening causes tripping of the circuit breaker D which interrupts the feeding of the tube L to be safeguarded. The contact c closes at the same time a signal or alarm system, say, an electric bell. The contact d, finally, keeps the coil of the relay R2 ener-

gized after extinction of the lamp B until pressure is brought to act upon the button M in order to release the same, thereby resetting the safety apparatus to an operative condition.

5 Having thus described my invention, what I claim is:

1. Safety device insuring protection against undue rises of temperature in transmitter tubes cooled by water circulation, comprising an inductive circuit, a safety circuit breaking means, said means comprising a photoelectric cell interposed between an electric light bulb fed with radio-frequency energy by induction from said inductive circuit in order to preclude all chances of direct 10 electric connection from the safety devices fed on low-potential current and the means responsive to the fluctuations of temperature which itself is maintained at the voltage of the anode.
2. A safety device insuring protection against 15 an undue rise of temperature comprising an electron tube having a metallic anode, means for supplying said anode with a high potential, means for liquid cooling said anode, means controlled by the liquid temperature and controlling a con- 20

tact, said contact being closed when the temperature rises above a predetermined limit, said last means being electrically connected with a high potential supply, a light source supplied by a circuit comprising an energy source and said contact, said light source being inductively coupled with a high frequency field generated by the oscillating circuit associated with said power tube. 5

3. A protective device for a vacuum tube having anode water cooling means, said device comprising a bi-metallic circuit breaking means, said circuit breaking means disposed within the anode water cooled outlet of said tube, an inductive circuit connected to the anode of said tube, an electric lamp connected in series with said inductive circuit and said circuit breaking means, a photo electric cell located so as to be actuated by the light of said electric lamp, a relay circuit connected to said photo electric cell whereby the energy supply circuit for said tube is broken when a pre-determined rise of temperature is reached in the anode of said tube. 10 15 20
